UNITED STATES PATENT OFFICE.

FRANK M. KAUFMAN, OF PHILADELPHIA, PENNSYLVANIA.

METHOD OF WEAVING MOHAIR FABRICS.

Application filed August 26, 1925. Serial No. 52,486.

My invention relates to mohair fabrics and more especially to such fabrics when woven with designs. Silk and cotton fabrics lend themselves readily to interweaving of designs, but it has heretofore been found commercially impractical to weave designs upon pile fabrics although designs upon such fabrics would be especially effective. The non-success of prior attempts to weave designs in pile fabrics was due to the fact that, with the method of weaving then in use, the short pile fibers were not gripped and held in position firmly enough to permit the successful interweaving of an additional fabric without impairing the appearance of the pile fabric.

The object of my invention is to provide a method of interweaving the design fabric without impairing the appearance of the pile fabric.

This object I attain in the following manner, reference being had to the accompanying drawings in which

Figure 1 is an exaggerated fragmentary diagrammatic section through a pile fabric woven in accordance with my invention,

Figure 2 a like view showing an added step in the weaving,

Figure 3 a fragmentary edge view of the fabric, and

Figure 4 an exaggerated diagrammatic section through the fabric after splitting.

In the drawings A denotes the weft threads and B, B¹, B² and B³ the warp threads which form the backing, C and C¹ the mohair strands, D the design threads, and Z, Z¹ and Z² the zero points in the cycle of operation.

For convenience the threads composing the two plies of the backing will be referred to as upper and lower. In weaving the fabric one series B of the upper warp threads and one series B² of the lower warp threads are placed under materially higher tension than the companion series B¹ and B³. As a result the tight threads are held practically straight and the weft threads are staggered, one being held above and the next below a straight warp thread.

Starting from Z, one mohair strand C passes over one upper weft thread, under the adjacent upper weft thread, over a third upper weft thread, then crosses diagonally to the lower ply of the backing. The other mohair strand C passes under a lower weft

thread, over the adjacent lower weft thread, under a third lower weft thread, then crosses diagonally to the upper ply of the backing, crossing the other mohair strand C at Z¹ and completing a half cycle of the mohair weaving. Strand C passes under a lower weft thread, over the adjacent lower weft thread, under a third lower weft thread, then crosses diagonally to the upper ply of the backing. Strand C passes over an upper weft thread, under the adjacent weft thread, over a third weft thread, then crosses to the under ply of the backing, crossing strand C at Z² and completing a cycle of mohair weaving, after which the weaving proceeds as before. In crossing from ply to ply of the backing the mohair strands avoid the weft thread directly opposite the one last engaged and the one next adjacent so that each strand engages with three weft threads in one ply, then three in the other ply and so on, but leaving the weft thread, in each strand, at the point of crossing disengaged. Each mohair strand is therefore interlocked with three weft threads before it crosses to the other ply of the backing and each section of the strand is firmly gripped in place when cut. Moreover, the staggered relation of the weft threads holds the ends of the strands in substantially perpendicular position instead of allowing them to extend at an angle as they do when the adjacent weft threads are parallel.

The design threads, D, of linen or other vegetable fiber, pass under a lower weft thread, over an upper weft thread, and so on.

Weaving in accordance with this method produces, when the original product is split, a smooth and even pile surface in which the pile strands are firmly gripped and a design may be interwoven without disturbing the pile strands or otherwise injuring the fabric.

The design threads, being of vegetable fiber and the pile strands of animal fiber, the design may be readily dyed of one color and the pile background of a contrasting color thereby producing a highly attractive fabric.

Having thus described my invention, what I claim as new and desire to secure by Letters Patent is:—

1. A method of weaving mohair fabrics consisting in applying a higher degree of tension to one series of backing warp threads than to its companion series, thereby causing the weft threads to be staggered above and

below the tight warp threads; weaving pile strands to interlock with three weft threads in each ply of the backing before crossing diagonally to the other ply and leaving every 5 fourth weft thread disengaged, weaving design threads over certain of the upper weft threads and under certain of said lower weft threads in accordance with a predetermined arrangement, and splitting the two-ply product substantially as described.

2. A method of weaving double pile fabrics consisting in applying a higher degree of tension to one series of backing warp than to its companion series, thereby causing the 15 weft threads to be staggered above and below the tight warp threads; weaving pile strands to interlock with a plurality of weft threads in each ply of the backing before crossing diagonally to the other ply and leaving certain 20 of said weft threads disengaged; weaving design strands between the two plies engaging predetermined weft threads in each; the pile strands and design strands being of animal and vegetable fiber respectively, or 25 vice versa, whereby the design may be dyed a different color from the body of the fabric,

and splitting the two ply product, substantially as described.

3. A method of weaving double pile fabrics consisting in applying a higher degree of 30 tension to one series of backing warp threads than to its companion series, thereby causing the weft threads to be staggered above and below the tight warp threads to form inner and outer weft threads, weaving pile strands to interlock with a plurality of weft threads in each ply of the backing before crossing to the other ply and leaving certain of said 35 weft threads disengaged, weaving design strands between the two plies to embrace outer weft threads in the lower ply and embrace the next successive inner weft threads in the upper ply, the pile strands and design 40 strands being of animal and vegetable fiber respectively, or vice versa, whereby the design 45 may be dyed a different color from the body of the fabric, and splitting the two-ply product, substantially as described.

In testimony whereof I have signed my name to this specification.

FRANK M. KAUFMAN.
